(57) **CLAIM**

The ornamental design for a bicycle saddle, as shown and described.

DESCRIPTION

FIG. 1 is a perspective view of a bicycle saddle showing my new design;

FIG. 2 is a top plan view thereof;

FIG. 3 is a side elevational view thereof;

FIG. 4 is a front elevational view thereof; and,

FIG. 5 is a rear elevational view thereof.

The broken lines (oval-shaped, in FIGS. 1 and 2) form no part of the claimed design.
